Primary Examiner—Ian Simmons

(74) Attorney, Agent, or Firm—Andrew G. Rozycski

(57) **CLAIM**

We claim the ornamental design for the biopsy device, as shown and described.

DESCRIPTION

FIG. 1 is an angled side view perspective of the biopsy device;

FIG. 2 is a front view of the biopsy device;

FIG. 3 is a back view of the biopsy device;

FIG. 4 is a left side view of the biopsy device;

FIG. 5 is a right side view of the biopsy device;

FIG. 6 is a top view of the biopsy device; and,

FIG. 7 is a bottom view of the biopsy device.
